UNITED STATES PATENT OFFICE.

GEORGE M. VON CULIN, OF PHILADELPHIA, PENNSYLVANIA.

SHUTTLE-MOTION.

No. 873,470.

Specification of Letters Patent.

Patented Dec. 10, 1907.

Application filed November 28, 1906. Serial No. 345,495.

To all whom it may concern:

Be it known that I, GEORGE M. VON CULIN, a citizen of the United States, and a resident of the city and county of Philadelphia, State 5 of Pennsylvania, have invented certain new and useful Improvements in Shuttle-Motions, of which the following is a specification.

My invention relates to improvements in shuttle movements for narrow fabric looms, 10 and the object of my invention is to furnish a means for carrying the shuttles in either direction quickly across the spaces in the batten of the loom when the lay is in a position near the greatest opening of the shed so 15 as to avoid all contact between the shuttle and warp, and which will permit the shuttle to remain entirely at rest after having been so actuated until the driving shaft of the loom has been turned nearly four-fifths of a 20 revolution.

In my invention the shuttles remain at rest for a considerable interval of time between each pick and therefore the operator is enabled to stop the loom to repair a broken 25 warp, &c. with less danger of injury to the fabric being woven than is possible with the use of the devices which cause the shuttles to be more constantly in operation.

In the accompanying drawing forming 30 part of this specification and in which similar letters of reference indicate similar parts throughout the several views:—Figure 1, is a side elevation of part of a loom embodying my shuttle operating means; Fig. 2, a plan 35 of Fig. 1; Fig. 3, a perspective view of part of the batten of the loom to show the connection between the straps and the rack operating the shuttles; Fig. 4, an enlarged side elevation of my means for driving and 40 for holding the shaft carrying the double crank which carries the straps for operating the shuttle actuating rack. Fig. 5, a plan of Fig. 4.

a is the main driving shaft of a loom, *b* a 45 gear wheel carried by shaft *a*, which meshes with and drives a gear wheel *c*; *d* is a segmental gear revolving with gear *c*, which during part of its revolution is in engagement with and driving a gear wheel *e* upon the 50 shaft *f* on which is a double crank *g* which carries one of the ends of two straps *h*—*i*. The straps *h*—*i* pass under pulleys *j*—*k*. Figs. 2 and 3, over pulleys *l*—*m*, Fig. 3, and their other ends are fastened to a rack *n*, Fig. 53, which by the movement of the straps, as dictated by the double crank *g*, draw the

rack *n* first in one direction and then in the other to actuate the shuttles *o* in a well known manner.

As has been stated the segmental gear *d*, 60 engages and drives the gear *e* to actuate the rack *n*, this movement is timed to take place when the shed is fully opened, or very nearly opened, and in order that the movement of the rack *n* may entirely cease when having 65 been drawn in either direction to its full extent and may there remain at rest until the shed is again opened I make use of the following device for holding the gear *e* rigidly at rest between the intervals of its operation by 70 the segmental gear *d*.

p is an arm fast to the gear *e*, or to the shaft *f*, and upon opposite ends furnished with notches *r*, *r'* which are adapted to be engaged successively by a tooth *s* which is 75 carried upon one arm of a bell-crank lever *t* which is pivoted at *u*. The other arm of this lever carries a friction roller *v* which is adapted to be engaged by a cam *w* which rotates with the segmental gear *d*. A spring *x* 80 normally holds the bell-crank in the position shown in Fig. 4.

The operation of the device is as follows: The gear *b* is driven by the main shaft *a* of the loom and drives the gear *c*, the segmental 85 gear *d* and the cam *w*. Presently the cam *w* engages the friction roller *v* on the bell-crank carrying this roller, this movement causes the arm of the bell-crank carrying the tooth *s* 90 to be lifted until the tooth is out of engagement with the notch *r* in the arm *p* with which it has until now been in engagement. As soon as the tooth and notch are out of engagement the segmental gear *d* is brought 95 into engagement with the gear *e* which it rotates one-half a turn. When the segmental gear *d* leaves the gear *e* the cam *w* leaves the roller *v* and the spring *x* brings the tooth *s* into the notch *r'* upon the end of the arm *p*. 100 The gear wheel *e* and the double crank *g* are thus rotated one-half a revolution for each complete revolution of the main driving shaft *a*, but owing to the ratio between the segmental gear *d* and the spur gear *e*, the 105 half revolution of the gear *e* is accomplished during one-fifth of the revolution of the main driving shaft.

The movement of the shuttles takes place only during the movement of the spur gear *e* 110 hence during four-fifths of the revolution, of the fly wheel the shuttles are at rest.

Having thus described my invention, I claim as new and desire to secure by Letters Patent:

- 5 1. In a shuttle motion for narrow fabric looms, in combination, with the main driving shaft of the loom, a shuttle actuating rack, means driven from the main shaft of the loom for reciprocating said rack, and means actuated by the movement of said
- 10 10 main shaft for locking said shuttle reciprocating means at the completion of each stroke of said rack and for unlocking said means immediately prior to each stroke.
- 15 2. In a shuttle motion for narrow fabric looms, in combination, a shuttle actuating rack, a shaft, a spur gear on said shaft, an arm on said shaft, furnished at points diametrically opposite with notches, a double crank

on said shaft, a segmental gear driven from the main shaft of the loom for intermittently 20 actuating said gear wheel, a bell crank lever, a stop carried by one arm of said lever for engaging the notches in said arm, a cam moving with said segmental gear for actuating said bell crank lever to cause a disengagement of said stop and notches, a spring normally causing said stop to engage one of 25 said notches, and connections between each of said cranks and the rack, one serving to move said rack in one direction, the other in 30 the other direction.

GEORGE M. VON CULIN.
